UNITED STATES PATENT OFFICE.

WILLIAM F. ENGLER AND JULIUS M. RUEDY, OF LOS ANGELES, CALIFORNIA.

RAILWAY-CROSSING SIGNAL.

1,304,035.

Specification of Letters Patent. Patented May 20, 1919.

Application filed July 9, 1917. Serial No. 179,555.

To all whom it may concern:

Be it known that we, WILLIAM F. ENGLER and JULIUS M. RUEDY, both citizens of the United States, residing at Los Angeles, 5 in the county of Los Angeles and State of California, have invented a new and useful Railway-Crossing Signal, of which the following is a specification.

Our invention relates to the art of preventing persons and vehicles from entering a railway crossing during a definite period before and during the time that a train or other vehicle is passing the crossing.

The principal object of the invention is 15 to provide a railway crossing signal of simple construction and operation which is so placed that it cannot be readily disregarded.

Referring to the drawings, which are for 20 illustrative purposes only:

Figure 1 shows a street intersection with the railway crossing provided with a single signal.

Fig. 2 shows an elevation of the same 25 signal.

Fig. 3 shows a diagram of connections, and

Fig. 4 shows rather diagrammatically a 30 method of operating the limit switches.

Fig. 5 is an enlarged view of the winch.

In the form of the invention illustrated in these drawings, the signal proper consists of a cross bar 11 having a warning signal 12 secured thereon and a series of pendent 35 lanterns 13, each lantern being equipped with a suitable incandescent lamp or other luminous source. The bar 11 is suspended by means of flexible cords 14 from any suitable structure, these cords passing into a

case 15 in which is located a standard winch or winding rig operated by an electric motor 16. This electric motor is preferably of the series type and consists of a field 17 and an armature 17'. Suitably located at some 40

point on one of the cords 14 are three buttons 18, these buttons being so placed that they operate a limit switch lever 19 and a limit switch lever 20. Secured on the limit 45 switch levers 19 and 20 are insulating blocks 21 to which are fastened conducting blocks

22. These conducting blocks 22 serve to make contact between fingers 23 and 24, and 25 and 26, as shown in Figs. 3 and 4. A 50 battery or other source of electric power 27 is supplied, and a relay 28 may also be used. The relay 28 consists of a winding 29 sur-

rounding a core 30 which carries an insulating block 31. Contactors 32 and 33 are connected through flexible cords 34 with terminals 35 and 36 carried on insulating blocks 37. Secured on the insulating blocks 37 are upper fingers 38 and 39 and lower fingers 40 and 41. The relay is so arranged that the contactors 32 and 33 are normally in contact with the fingers 40 and 41. 60

Each lantern 13, above referred to, consists of a conical shell 45 of sheet metal, the lower end of which is provided with a guard for the lamp consisting of semi-circular wire mesh 46 secured to the shell 45 in any well known manner. These lanterns are so arranged as to hang in their lowered position, so that vehicles such as automobiles or cars, may pass freely thereunder. In the event, however, that higher objects, such as a load 75 of hay, come into contact with one or more of the lanterns, the flexible suspension will bend, and allow the objects to pass. A battery 50 is provided, and insulated rail sections 51 and 52 are also provided. 80

The method of connection is as follows:

Winding 29 of the relay 28 is connected through the battery 50 with the rail 51, and through a wire 53 with the rail 52, the wheels and axle 54 of the vehicle using rail 85 sections 51 and 52, serving to connect the sections 51 and 52 together, and to actuate the relay 28 by raising the core 30.

The armature 17' is connected on one side to the finger 24 and on the other side to 90 the finger 25.

The field 17 is connected on one side to one terminal of the battery 27, the other side of this battery being connected to the terminal 35. The other side of the field 17 95 is connected to the terminal 36. The finger 40 is connected to the finger 26, and the finger 41 is connected to the finger 24. The finger 39 is connected to the finger 25, and the finger 38 is connected to the finger 23. 100

The method of operation is as follows:

With the parts in the position shown in full lines in Fig. 2, and the electrical apparatus in the position shown in Fig. 3 the following condition of affairs will be seen 105 to exist.

Contacts 23 and 24 are connected together through the block 22, which is held in this position by the central button 18, which is in its left-hand position. All circuits are 110 open until the wheel and axle 54 connect the rails 51 and 52 together. Whenever this oc-

5 curs, the relay 28 is actuated and contactors 32 and 33 are pulled up, making contact with the upper fingers 38 and 39, respectively. The current then flows from the battery 27 through the field 17 to the terminal 36, through the contactor 33 to the finger 39, through the armature 17', through the fingers 23 and 24, and block 22, to the finger 38, and through the contactor 32 and the 10 flexible cord 34 to the terminal 35 which is connected to the other side of the battery, thus completing the circuit.

The motor being actuated through the current flowing in the armature 17' and field 17, the winch is actuated to lower the bar 11 through the flexible cords 14, these cords moving in the direction of the arrow A, as shown in Fig. 4. This lowers the lanterns 13 from the position shown in full lines in Fig. 2 to the position shown in dotted lines in that figure. Whenever the flexible cord 14 reaches this position, one of the end buttons 18 strikes lever 19 and opens the circuit to the motor by throwing the block 22 away from between fingers 23 and 24. Simultaneously with this movement, the other end button 18 strikes the switch lever 20 and throws the block 22 into contact with fingers 25 and 26. The lanterns 13 then hang suspended just above the tops of passing vehicles. Incandescent lamps may be provided in lanterns 13, and suitable switch mechanism may be provided for turning them on and off, these lamps being lighted when lanterns are in their extreme lower position, or while being lowered.

Whenever the wheel and axle 54 pass off the rail sections 51 and 52, the circuit of the winding 29 of the relay 28 is opened and the core 30 falls. This allows the contactors 32 and 33 to assume their normal position, resting on the lower fingers 40 and 41. The fingers 25 and 26 being connected through the block 22, current flows from the battery 27 through the field 17 to the terminal 36, and through the contactor 33 to the finger 41. From this finger it flows through the armature 17' to the finger 25 and from that finger through the block 22 to

the finger 26. From the finger 26, it flows 50 to the finger 40, and through the contactor 32 and the terminal 33 to the other side of the battery 27. This starts the winch, thus raising the bar 11 through the flexible cords 14. This continues until one of the outside 55 buttons 18 strikes the lever 20, opening the circuit between the fingers 25 and 26, the central button 18 simultaneously striking the lever 19 and closing the circuit between the fingers 23 and 24. The circuit being open 60 between the fingers 25 and 26, the motor will stop and the signal will remain in its raised position until such time as it is again actuated by the wheels and axle 54 of a succeeding train. 65

We claim as our invention:—

A crossing signal comprising a stationary supporting structure located at either side of a roadway which it is desired to protect and extending across said roadway at a sufficient height to give ample clearance to the traffic on said roadway; a cross bar substantially parallel with the surface of said roadway and of sufficient length to cover the major portion of the width of said roadway; 70 a series of pendant lanterns on said cross bar; two pulleys each secured to said structure over said roadway, said pulleys being separated from each other by a distance slightly less than the length of said bar; two 80 flexible cords each secured to said bar near the end thereof and each passing through one of said pulleys; winding means secured in said structure for raising and lowering said cross bar in a position substantially 85 parallel to the surface of said roadway by winding up or unwinding said flexible cords each substantially the same distance and means for arresting the movement of said bar at a sufficient height above the roadway 90 to allow vehicles to pass under said pendant lanterns.

In testimony whereof, we have hereunto set our hands at Los Angeles, California, this 2nd day of July, 1917.

WILLIAM F. ENGLER.
JULIUS M. RUEDY.
